(57) **CLAIM**

I claim the ornamental design for a folder, as shown and described.

DESCRIPTION

FIG. 1 is a front/right/top perspective view of a first embodiment of the folder for which a front/left/top perspective view thereof would be a mirror image thereof;

FIG. 2 is a front elevational view thereof, for which a rear elevational view thereof would be identical;

FIG. 3 is a top plan view thereof;

FIG. 4 is a bottom plan view thereof;

FIG. 5 is a right side elevational view thereof; and

FIG. 6 is a left side elevational view thereof.

FIG. 7 is a front/right/top perspective view of the first embodiment of the folder, shown partially open.

FIG. 8 is a front elevational view of the first embodiment, with the gusset optionally extended out, which configuration might be used for packaging and shipping.

FIG. 9 is a front/right/top perspective view of a second embodiment of the folder for which a front/left/top perspective view thereof would be a mirror image thereof;

FIG. 10 is a front elevational view thereof, for which a rear elevational view thereof would be identical;

FIG. 11 is a top plan view thereof;

FIG. 12 is a bottom plan view thereof;

FIG. 13 is a right side elevational view thereof; and

FIG. 14 is a left side elevational view thereof.

FIG. 15 is a front/right/top perspective view of the second embodiment of the folder, shown partially open; and,

FIG. 16 is a front elevational view of the second embodiment, with the gusset optionally extended out, which configuration might be used for packaging and shipping.
